Primary Examiner — Clint A Samuel(74) *Attorney, Agent, or Firm* — Prakash Nama; Global IP Services, PLLC(57) **CLAIM**

The ornamental design for a quantum lamp, as shown and described.

DESCRIPTION

FIG. 1 is a perspective view of a quantum lamp showing my new design;

FIG. 2 is another perspective view thereof;

FIG. 3 is an exploded view thereof;

FIG. 4 is a front view thereof;

FIG. 5 is a back view thereof;

FIG. 6 is a left side view thereof;

FIG. 7 is a right side view thereof;

FIG. 8 is a top plan view thereof; and,

FIG. 9 is a bottom plan view thereof.

The broken lines in the drawings depict portions of the quantum lamp that form no part of the claimed design.
